ROTARY JAR

Haskell C. Collett, Los Angeles, Calif.

Application May 15, 1935, Serial No. 21,510

20 Claims. (Cl. 255—27)

My invention relates to a rotary jar used in fishing work in well drilling, and my invention pertains to a type known as automatic torque control rotary jars. In this type a twist is given to the drill pipe or drill string after the tool has been secured to a fish, then the upward tension or pull on the drill pipe causes the tripping of the tool or jar when approximately a predetermined upward pull is developed, thus giving a striking blow which may be approximately predetermined. With this type the force of the blow may be varied by the twist given to the drill string, together with the tension of the upward pull.

In the above mentioned type of rotary jar my tool embodies the feature of providing for a threaded connection between the drill string or tubing used to support the jarring tool and a fishing tool, the threading action being transmitted through the jarring tool.

20 In my invention one of the main objects and features is the provision of a strong and substantial upper mandrel having a coarse thread with a long lead, the threads being continuous and such mandrel being used to develop a rotating action 25 of a sleeve member within a tubular body, the tubular body being non-rotatably connected to a lower mandrel sub and fishing tool.

Another object and feature of my invention is in requiring a positive predetermined and relative 30 rotation between a sleeve actuated by the threaded mandrel in a turning motion and this sleeve being provided with end abutting splines coaxial with complementary splines on a lower mandrel connected to the fish. These splines must 35 be rotated out of end registration to align with the alternate grooves and thus allow the tripping of the jar.

Another feature of my invention resides in the interconnection of the lower mandrel which is 40 attached to the fish and the slideable body having the knocking sub by which the lower mandrel and the tubular body structure are prevented from relative rotation, these being guided in the hammer or jarring stroke by these interengaging 45 splines.

Another object and feature of my invention is in the combination of the upper mandrel with the coarse threads of a long lead connected to the upper sub, which in its turn is attached to the 50 drill string, and the lower mandrel sub which is connected to the lower end has the lower mandrel threaded therein. This lower mandrel is provided with a collar forming an anvil. The tubular body is connected to the upper threaded 55 mandrel by a body sub at its upper end and at

its lower end carries a knocker sub which strikes on the anvil of the lower mandrel and gives the jarring action.

With this combination I employ the spline connection of the lower mandrel having the anvil and the tubular body by sliding constantly meshing splines and causing the tripping of the jar by a rotatable sleeve which has the end to end registering splines with the lower mandrel which carries the anvil.

With this combination I employ the spline connection of the lower mandrel having the anvil and the tubular body by sliding constantly meshing splines and causing the tripping of the jar by a rotatable sleeve which has the end to end registering splines with the lower mandrel which carries the anvil.

A further feature of my invention is the construction for giving a slight rotation of the sleeve, this being by means of interengaging end fingers on the upper mandrel which has the coarse threads and the sleeve. This gives a sufficient 15 rotation of the sleeve to disengage the end to end bearing of the splines and allowing the tripping of the jar.

A further detail feature of my invention is that these end to end abutting splines have surfaces 20 at right angles, or normal to the axis of the tool and thus are not required to develop any twist, this twist being done by the coarse threads on the upper mandrel working in connection with the upper body sub.

A further detail feature of my invention is providing for the flow of the slushing mud by having a slushing fluid pipe threaded on the bore of the upper threaded mandrel. This pipe extends into the bore of the lower mandrel and has a packed joint seal with the lower mandrel so that the slushing mud is forced downwardly directly through the whole jarring tool.

My invention is illustrated in connection with 35 the accompanying drawings, in which

Fig. 1 is a vertical section through the jarring tool, the upper mandrel, the rotating sleeve and the lower mandrel with the anvil being shown in elevation;

Fig. 2 is a vertical section through the upper part of the tool above the anvil of the lower mandrel, showing the upper mandrel and the sleeve in section.

Fig. 3 is a vertical section of the lower part 45 of the tool connecting with Fig. 2, and showing the lower mandrel and the anvil connected thereto in section.

Fig. 4 is a transverse section on the line 4—4 of Figs. 1 and 2, taken in the direction of the 50 arrow.

Fig. 5 is a transverse section on the line 5—5 of Figs. 1 and 2, taken in the direction of the arrows.

Fig. 6 is a transverse section on the line 6—6 55

of Figs. 1 and 2, taken in the direction of the arrows.

Fig. 7 is a vertical section partly broken away to illustrate the tripping action of the butt and splines on the rotatable sleeve and the upper end of the lower mandrel, the body being omitted.

In my invention I employ an upper sub 11 which may be connected to a drill pipe or tubing by the ordinary type of threaded connection. Connected to this upper sub I employ an upper mandrel 12, this having a threaded connection preferably by providing the upper sub 11 with a box 13 and the upper end of the upper mandrel 15 with a tapered threaded pin 14, this being a standard threaded connection. The upper mandrel 12 is provided with coarse threads 15, these threads preferably being substantially square threads with a long lead so that considerable movement endwise is necessary to develop the degree of twist required. Below the threads there is a short neck portion 16 and a lower head 17, this being cylindrical on its periphery and having downwardly projecting fingers 18. These fingers form part of a cylinder extending downwardly on their outside from the periphery of the head 17; the inside diameter being such that the fingers are of sufficient thickness in a radial direction to provide adequate strength. The upper mandrel has a bore 19 in registry with the bore 20 of the upper mandrel sub 11.

Threaded on the coarse threads 15 of the upper mandrel there is a body sub 21. This has a squared upper end 22, a cylindrical periphery 23 and a squared lower end 24. It is provided with a tapered thread 25 terminating at a lower shoulder 26. The sub is threaded its full length and thus has a complete engagement with the full threads 15 on the upper mandrel when the parts are in the position shown in Figs. 1 and 2, prior to the tripping on the jarring stroke.

A tubular body 30 has a tapered thread 31 at its upper end connecting with the thread 25 of the body sub 21 and having its upper end 32 abutting against the shoulder 26, these parts when assembled having a soft annular weld 33. The lower end of the tubular body 30 has an internally tapered thread 34 extending upwardly from the lower end 35. The knocker sub 36 has an externally tapered thread 37 from its upper end 38 which is squared, this terminating in a shoulder 39 engaging the end 35 of the tubular body 30 and at this connection there is a soft annular weld 40. The knocker sub has a squared lower end 41; the periphery 42 of the knocker sub, the body 30, the body sub 21 and the lower portion of the upper mandrel sub being all the same. The knocker sub 36 has a large internal cylindrical bore defined by the measurement 43. The upper end 38 of the knocker sub forms the hammer of the jar.

Slidably mounted in the bore 43 of the knocker sub 36 there is a lower mandrel 45. This has a cylindrical section 46 operating in the bore of the knocker sub 36 and at its lower end it is connected to the lower mandrel sub 47. This sub preferably has a tapered threaded box structure 48 engaging the externally threaded threads on the pin 49 at the lower end of the lower mandrel. This lower mandrel sub 47 is connected to the fishing tool or may incorporate part of the fishing tool. The lower mandrel has an axial bore 50 for the slushing of mud, which registers with the bore 51 of the lower mandrel sub.

The anvil structure 55 consists of a substantial collar formed integral with the upper cylindrical portion 46 of the lower mandrel 45 and this has a squared anvil shoulder 56. This anvil is cylindrical on its periphery 57 but is provided with a number, preferably four, shallow longitudinal grooves 58 which may be preferably each semi-cylindrical.

The interconnection between the tubular body 30 and the lower mandrel 45 to transmit a twisting action and to give a longitudinal guide during the jarring stroke, comprises providing an internally thickened section 65 on the body 30. This thickened section has a lower annular shoulder 66 and an upper annular shoulder 67. This thickened section is provided with longitudinal splines 68 (note Fig. 6). In the illustration these splines are shown as six in number and these engage with outwardly extending splines 69 formed integral with the lower mandrel 45 above the anvil 55, there being preferably a short space 70 between the upper surface of the anvil and the lower edge 71 of the splines 69. In the illustration there are six splines 69 on the lower mandrel. These interengaging splines 68 and 69 transmit the twist or rotational forces between the upper mandrel sub 11 through the medium of the upper mandrel 12, the body sub 21, the body 30, the lower mandrel 45 to the lower mandrel sub 47.

An important feature of my invention is in the construction and use of the loose or rotatable sleeve 75. This sleeve fits inside of the upper portion of the tubular body 30 immediately below the head 17 of the upper mandrel 12 and above the thickened portion 65 having the internal splines 68. This sleeve is cylindrical on its outside surface and has a lower transverse end 76 with an upper end 77 and an inner bore 78 of large diameter. The upper portion of the sleeve is provided with longitudinal fingers 79 which engage between the fingers 18 depending from the head 17 of the upper mandrel 12. Thus by the interengagement of these fingers a rotational turn on its axis may be given to the sleeve 75 in relation to the body 30 by the rotational action of the upper mandrel 12.

The structure forming the tripping medium between the sleeve and the lower mandrel 45 consists of internal splines 85 extending upwardly from the lower portion of the sleeve, that is from the end 76 (note Figs. 2 and 5). These splines have an upper contact end 86 which is designed to engage and contact with the lower contact face 87 of the external splines 88 which are formed on the upper portion 89 of the lower mandrel 45. These splines 88 and the upper end of the lower mandrel 45 terminate at 90. The contact ends 86 and 87 of the splines on the sleeve and the upper splines on the lower mandrel form an annular surface normal to the axis of the tool and prior to the tripping for the jarring stroke are in end to end engagement and in alignment as shown in Fig. 5. This leaves longitudinal spaces 91 extending from the upper end 90 of the lower mandrel 45 to the lower end 76 of the sleeve 75.

The slushing fluid connection employs a wash pipe 95 which has a threaded connection 96 to the lower end of the upper mandrel 12 connecting with the bore 19 of this mandrel. This wash pipe passes through a packing gland nut 97 threaded into a recess 98 in the upper part of the bore 50 of the lower mandrel 45. Packing rings 99 are fitted into the recess below the gland nut and

thus make a water-tight seal where the wash pipe enters the bore 50 on the lower mandrel 45, the wash pipe having a sliding fit in this bore. By this means the slushing mud may be conveyed

5 through the jarring tool without any leakage.

In the body at the travel space for the jarring stroke, that is between the end 38 of the rocker sub and the anvil shoulder 56, of the anvil collar 55, I provide perforations 100 to allow discharge 10 of the slushing fluid during the hammer stroke. These allow the slushing fluid to flow outwardly 15 from the annular space between the lower mandrel 45 and the lower portion of the body 30. I provide longitudinal grooves 58 in the anvil collar 15 55, these being on the periphery to provide for free flow of the slushing fluid past this anvil collar.

To facilitate the release or tripping of the butt 20 and splines 85 on the sleeve 75 from the lower end of the splines 88 on the upper portion of the lower mandrel 45, I provide a slight rounding 105 on the splines 85 at the corners formed by the horizontal upper faces 86 and the vertical radial edges 106. In a complementary manner I form 25 slightly curved corners 107 on the splines 88 formed integral with the lower mandrel 45 at the corners formed by their lower transverse ends 87 and their vertical radial faces 108. Thus on the 30 jarring stroke when there is an upward pressure on the sleeve, due to the lower end of the sleeve resting on the upper edge of the internally thickened section 65 of the body 30 and when the sleeve is rotated due to the action of the upper mandrel 12 in connection with the body sub 21, 35 at the moment of release of the splines 85 and 88 one from another, these rounded edges 105 and 107 engage and not only cause a quick release of these butt and splines but prevent breaking down of the metal at these vertical radial edges of the splines due to the great pressure 40 developed on a comparatively small body of metal.

The manner of operation and functioning of the tool is substantially as follows: When it is lowered into the well, the various parts are in the relative positions shown in Figs. 1, 2 and 3. When a fish is properly engaged by the fishing tool the drill string connected to the upper mandrel sub 11 may be twisted to properly tighten 45 all threaded joints or connections. This may be done by employing the rotary table through which operates the ordinary kelly of the drill string or with my tool the drill string may be twisted by tongs. The twist is released by releasing the rotary table, allowing releasing of the 50 twist incorporated in the drill pipe. Then an upward pull is exerted on the drill string. As the fish is caught in the hole, that is the bore of the well and thus cannot rotate, the lower mandrel 55 45, the body 30 and the body sub 21 are held from rotation. As the upward pull increases the threaded upper mandrel 12 may twist in the body sub 21. It will be understood that in this upward pull, the upper ends 110 of the thickened portions 60 65 of the body and the upper surface of the internal splines 68 engaging the lower end of the sleeve 75, causes a considerable end to end butt pressure on the splines 85 on the sleeve and the lower surface of the splines 88 of the upper end 70 89 of the lower mandrel 45; that is, there is considerable pressure developed between the upper surface 86 of the splines 85 of the sleeve and the lower surface 87 of the splines 88 of the lower mandrel. However, the mandrel is free to rotate

on its axis and this rotation is tensioned by the rotation or twist given to the threaded upper mandrel 12 which is secured to the drill string reacting against the threads of the fixed body sub 21. The slight rotation of this upper mandrel 5 12 causes the fingers 18 on its lower head 17 to operate against the upwardly extending fingers 19 of the sleeve to rotate the sleeve. In this action the space formed by the neck 16 between the lower end 24 of the body sub 21 and the 10 upper surface of the lower head 17 is decreased; but nevertheless the fingers 18 on the upper mandrel 12 and the fingers 18 on the sleeve 75 always remain in engagement.

When there is sufficient rotation given to the 15 sleeve to bring the corners 105 and 107 of the splines 85 and 88 respectively into pressure engagement as illustrated particularly in Fig. 7, the rounded edges together with the interengaging threads of the upper mandrel 12 and the body 20 sub 21, cause a quick tripping of the splines 85 and 88, releasing the tool for the jarring stroke. This jar is then given by the contact of the upper or hammer surface 38 of the knocker sub 36, 25 striking the anvil face 56 of the anvil collar 55 formed integral with the lower mandrel 45. This therefore gives an upward jar on the lower sub 41, the fishing tool and the fish in the well.

The tool is reset by merely lowering the drill 30 string by releasing the tension thereon which gives a first longitudinal travel of the body and sleeve relative to the lower mandrel due to the interengagement of the various splines and then a rotating action when the upper mandrel 12 is 35 forced downwardly by the weight of the drill string into the body sub 21; this rotating the upper mandrel 12 and the sleeve 75 in a reverse direction to split the splines 85 on the sleeve underneath the lower ends of the splines 88 on the upper end of the lower mandrel. The tool is 40 then in position for another jarring stroke.

If it is found that the jar or hammer action is not sufficiently severe, an initial twist may be given to the drill string, either by the rotary table or by tongs and the up pull then developed on the 45 drill string. The resistance developed to the relative rotation of the upper body mandrel 12 and the body sub 21 together with the frictional resistance of the slipping of the contact ends of the splines 85 and 88, regulate the tension required in the drill string to cause the tripping of the jar and to give the jarring stroke and hence 50 regulate the force of this stroke.

In the jarring stroke the sleeve 75 is carried up 55 with the body as it bears on the shoulder 67. Therefore on the return lowering stroke the sleeve 75 is usually carried to its lowermost position so that the splines on the sleeve and the upper splines on the lower mandrel may come into end to end abutting relation. However, should this not occur an up pull on the drill string with a second or third slight drop causes the sleeve to slip downwardly so that it may be positively rotated. In order to reduce the wear on 60 the shoulder 67, in some cases I employ a hard metal washer 110.

Various changes may be made in the details of construction without departing from the spirit or scope of the invention as defined by the 70 appended claims.

I claim:

1. In a rotary jar, the combination of a lower mandrel having an anvil secured thereto, the lower mandrel having means for connecting to 75

- a fish, an upper mandrel having means for connecting to a drill string, a body structure having a slideable connection on the lower mandrel and having a hammer member, a rotatable member in the said body having means interengaging with the lower mandrel and means actuated by the upper mandrel to rotate the rotatable element to trip the interengaging means between the rotatable element and the lower mandrel to release the jar for a jarring stroke.
2. A rotary jar having in combination a lower mandrel having means for connection to a fish, a tubular body structure slideable but non-rotatably connected to the lower mandrel, the lower mandrel having an anvil structure and the body having a hammer structure, an upper member having means for a rigid connection to a string of drill pipe, a rotatable member mounted in the body, interengaging restraining means between the rotatable member and the lower mandrel to maintain the hammer and anvil apart, and means to rotate the said element by the relative movement of the upper member and the body to release the restraining means to effect a jarring stroke between the hammer and anvil members.
3. A rotary jar having in combination a lower member having means for rigid connection to a fish, an upper member having means for a rigid connection to a drill string, a body structure slideable but non-rotatably mounted on the lower member, the lower member having an anvil structure and the body having a hammer structure, a rotatable member mounted between the lower member and the body, said rotatable member and the lower member having interacting restraining means to maintain the hammer and anvil apart, the upper member having a wedge type of connection with the body to cause a positive rotation of the upper member on an upward pull by the drill string, said upper member having means to rotate the rotatable member to disengage the restraining means and permit a jarring blow by the hammer on the anvil.
4. A rotary jar having in combination a lower member having means to form a non-rotatable connection to a fish, an upper member having means forming a rigid connection to a drill string, a body structure slideable by non-rotatably mounted on the lower member, the said body having a hammer and the lower member having an anvil, a rotatable sleeve, interengaging restraining splines on the sleeve and the lower member adapted to be positioned in end abutting relation, a wedge type of connection between the upper member and the body, whereby on an upward pull on the string, the upper member is rotated, an interconnection between the upper member and the sleeve to rotate the sleeve to disengage the butt end restraining splines and thereby trip the jar and permit a jarring blow by the hammer on the anvil.
5. A rotary jar having in combination a lower member having means for a rigid connection to tools to be removed from a well, an upper member having means for rigid connection to a drill string, a body structure slideable but non-rotatably mounted on the lower member, the lower member having an anvil, the body having a hammer, a rotatable member having a restraining structure, the lower member having a complementary restraining structure, said structures having contact surfaces at right angles to the axis of the body, said restraining structures retaining the hammer and anvil in spaced relation, an interconnection between the upper member and the body to rotate said upper member on an upward pull of the drill string, a connection between the upper member and the rotatable member to rotate said rotatable member to bring the contact surfaces of the restraining structures out of engagement and to permit the upward movement of the hammer to strike the anvil in a jarring blow.
6. A rotary jar as claimed in claim 5, the connection between the upper member and the body being such as to cause a reverse rotation of the upper member on lowering of the drill string after a jarring blow, the connection between the upper member and the rotatable member being such as to give a reverse rotation to the rotatable member to bring the restraining structures with their contact faces again into contact, whereby a second blow may be given by an upward pull on the drill string.
7. A rotary jar as claimed in claim 5, the connection between the upper member and the rotatable member being such as to permit a slight upward movement of the upper member relative to the body on an upward pull on the drill string, and a slight separation of the upper member and the rotatable member.
8. A rotary jar having a lower member with means for a rigid connection to a tool to be loosened from a well, an upper member having means for a rigid connection to a drill string, a body slideable but non-rotatably mounted on the lower member, the lower member having an anvil, the body having a hammer, a rotatable member below the upper member and having a lower end at right angles to the axis of the body, the said body having complementary shoulders at right angles to its axis to engage the lower end of the rotatable member, the rotatable member having a restraining structure, the lower member having a complementary restraining structure, said structures having end contacts to maintain the anvil and hammer in spaced relation, a wedging type of connection between the upper member and the upper portion of the body to exert an upward pull on the body and a rotational twist to the upper member on an upward pull on the drill string, the upward pull on the drill string transmitting an upward pressure on the lower end of the rotatable member and producing a pressure between the contact surfaces of the said restraining structures, an interconnection between the upper member and the rotatable member to rotate said latter member on the upward pull on the drill string to bring the contact surfaces of the restraining structure on the rotatable member out of engagement with the contact surfaces of the restraining structure on the lower member and thereby trip the jar to give a jarring blow between the hammer and the anvil.
9. A rotary jar as claimed in claim 8, the contact surfaces between the restraining structures on the rotatable member and the lower member being at right angles to the axis of the body.
10. A rotary jar having a lower mandrel with means for a rigid connection to a tool to be removed from a well, an upper mandrel having means for rigid connection to a drill string, a tubular body slideably but non-rotatably mounted on the lower mandrel, the body having a hammer surface, the lower mandrel having a collar forming an anvil, a sleeve rotatably mounted in the body and surrounding an upper portion of the lower mandrel, the said sleeve and the mandrel each having complementary restraining structures with contact surfaces at right angles to the axis of the sleeve and the lower mandrel, said

restraining structures holding the anvil and hammer in spaced relation, a wedging type of connection between the upper mandrel and the upper end of the body to transmit a pull on the body and a rotational twist to the upper mandrel on an upward pull on the drill string, an interconnection between the body and the sleeve to exert an upward pressure on the sleeve by the upward pull on the body, interengaging means between the upper mandrel and the sleeve to rotate the sleeve and disengage the contact surfaces of the restraining structures on the sleeve and the lower mandrel to thereby trip the jar and permit a jarring blow by the hammer on the anvil.

11. A rotary jar as claimed in claim 10, the interconnection between the upper mandrel and the sleeve comprising interengaging fingers, said fingers permitting a slight longitudinal separation of the upper mandrel and the sleeve due to an upward pull on the drill string.

12. A rotary jar as claimed in claim 10, the interconnection between the upper mandrel and the body and the upper mandrel and the sleeve being such as to first lower the sleeve on lowering of the drill string and secondly to rotate the sleeve relative to the lower mandrel to again bring the contact surfaces of the restraining structures on the lower mandrel and the sleeve into engagement.

13. A rotary jar having a lower mandrel with means for a rigid connection to a tool to be loosened from a well, an upper mandrel having means for a rigid connection to a drill string, a body having a spline connection to the lower mandrel to permit a longitudinal movement of the body on the lower mandrel but to prevent relative rotational movement, the body having a knocker sub with a hammer surface, the lower mandrel having a collar forming an anvil, a rotatable sleeve having restraining splines, the lower mandrel having complementary restraining splines, said splines having end abutting surfaces, which when in engagement maintain the hammer and anvil spaced, a wedging type of connection between the upper mandrel and the upper portion of the body to develop a pull on the body and a rotational twist on the upper mandrel on an upward pull on the drill string, interengaging surfaces between the body and the sleeve to exert an upward pressure on the sleeve during an upward pull on the body, interengaging fingers between the upper mandrel and the sleeve to rotate the sleeve on rotation of the upper mandrel to disengage the contact surfaces of the splines on the sleeve and on the lower mandrel and thereby trip the jar to give a jarring blow between the hammer and the anvil, the said splines on the sleeve and the complementary splines on the lower member guiding the sleeve in a rectilinear motion relative to the lower mandrel during the jarring blow.

14. A rotary jar as claimed in claim 13, the wedging type of connection between the upper mandrel and the body comprising external helical coil threads on the upper mandrel engaging with complementary internal threads on the upper part of the body.

15. A rotary jar as claimed in claim 13, the upper and lower mandrels each having a bore in alignment, a pipe connected to one mandrel and having a sliding fit in the bore of the other mandrel with a packing to prevent leakage.

16. A rotary jar having an upper mandrel with means for connection to a drill string, said man-

drel having depending fingers, a tubular body structure having a rotatable wedging connection to the upper mandrel, a lower mandrel having a slideable but non-rotatable connection to the body, the lower mandrel having means for connection to a fish, a rotatable sleeve in the body having fingers engaging the fingers of the upper mandrel, the lower mandrel and the body having complementary striking surfaces, splines on the sleeve and the lower mandrel, which when in end abutting relation retain the striking surfaces apart, the upper mandrel being adapted to develop a slight rotation on an upward pull on the upper mandrel, the said fingers communicating a rotation to the sleeve to disalign the splines of the sleeve and the lower mandrel, interengaging means between the body and the sleeve to exert an upward pressure on the sleeve during an upward pull on the upper mandrel, whereby on release of the aligned splines of the sleeves and the lower mandrel, a jarring blow is given by the said striking surfaces.

17. A rotary jar as claimed in claim 16, the engaging surfaces of the splines on the sleeve and the splines on the lower mandrel when in alignment being at right angles to the axis of the lower mandrel, the said splines having convexly rounded corners to facilitate their release at the moment of tripping the jar.

18. A rotary jar having an upper mandrel with means for attachment to a drill string, a helicoidal thread and annular depending fingers, a tubular body having an upper structure with a helicoidal thread engaging the thread of the upper mandrel, a transverse shoulder, a lower mandrel in the body, means to prevent relative rotation of the body and the lower mandrel, but permit longitudinal sliding, contact structures in the body and the lower mandrel to give a jarring blow, the lower mandrel having means for connection to a fish, a housed sleeve in the body having its lower end bearing on the said shoulder and fingers engaging with the fingers of the upper mandrel, the sleeve having splines, the upper mandrel having complementary splines, said splines having contact surfaces, which when in engagement hold the contact structures of the body and the lower mandrel spaced apart, whereby an upward pull on the upper mandrel develops a relative rotation of the upper mandrel and the sleeve, the upper mandrel by means of the fingers rotating the sleeve to disalign the splines of the sleeve and the lower mandrel, the shoulder engagement of the body and the sleeve developing a pressure on the engaging surfaces of the splines of the sleeve and the lower mandrel, the release of the splines tripping the jar to develop a jarring blow between the said contact structures.

19. A rotary jar as claimed in claim 18, the upper mandrel being adapted when lowered after a jarring blow to have a relative rotation in regard to the body and to first lower the sleeve in reference to the lower mandrel and then rotate the sleeve to again align the splines of the sleeve and the lower mandrel.

20. In a rotary jar, a tubular sleeve having a shoulder at the bottom, a plurality of splines, fingers at the top of the sleeve, a lower mandrel having splines, the splines of the sleeve and the mandrel having contact surfaces when in end to end alignment at right angles to the axis of the mandrel, the said splines having convexly rounded corners to facilitate tripping of the sleeve in reference to the mandrel at the moment

the contact ends of the splines disengage, means to develop an upward pressure on the sleeve to cause considerable friction for the disalignment of the said splines, and means operative by an upward pull to rotate the sleeve in reference to the lower mandrel to disalign the splines, where-

5
by the splines on the sleeve have an upward sliding motion relative to the splines of the lower mandrel, the said splines guiding the sleeve in a rectilineal sliding motion in regard to the lower mandrel.

HASKELL C. COLLETT.
